(57) **CLAIM**

The ornamental design for a storage bag, as shown and described.

DESCRIPTION

FIG. 1 is a top perspective view of the storage bag showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top perspective view of another embodiment of the storage bag shown in FIG. 1;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top perspective view of another embodiment of the storage bag;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

In FIGS. 8 to 10 and FIGS. 15 to 17, the breakaway portions show that the storage bag has no specific width. The broken lines shown in the drawings illustrate portions of the design that form no part of the claim. The dot-dash lines show unclaimed boundaries and form no part of the claim. The dash-dot-dot-dash lines show unclaimed boundaries and form no part of the claim.
